(57) **CLAIM**

I claim the ornamental design for a plug-in, energy saving, electrical capacitance device, as shown and described.

DESCRIPTION

FIG. 1 is a front view of a plug-in, energy saving, electrical capacitance device of the present invention;

FIG. 2 is a top view thereof;

FIG. 3 is a right side view thereof;

FIG. 4 is a bottom view thereof;

FIG. 5 is a rear view thereof;

FIG. 6 is a left side view thereof;

FIG. 7 is a top, perspective view thereof; and,

FIG. 8 is a bottom, perspective view thereof.

The broken line showing in FIGS. 1-8 represents unclaimed

subject matter and forms no part of the claimed design.
